UNITED STATES PATENT OFFICE.

ELMER M. JONES, OF ATLANTA, GEORGIA, ASSIGNOR TO JONES SIGNAL SYSTEM COMPANY, A CORPORATION OF GEORGIA.

AUTOMATIC TRAIN-STOP AND SIGNAL MECHANISM.

1,129,200.

Specification of Letters Patent. Patented Feb. 23, 1915.

Application filed October 14, 1910. Serial No. 587,053.

To all whom it may concern:

Be it known that I, ELMER M. JONES, a citizen of the United States, residing at Atlanta, in the county of Fulton and State 5 of Georgia, have invented a certain new and useful Improvements in Automatic Train- Stops and Signal Mechanism, of which the following is a full, clear, and exact description, reference being had to the accompanying drawings.

The object of this invention is to provide in a simple and effective form, mechanism for automatically giving an indication on a moving vehicle of track conditions—either 15 by applying the brake automatically or giving some other indication, as desired.

My invention is well adapted for use in conjunction with an electric signal system, employing track rails or a portion thereof 20 as conductors, whereby the mechanism may be set to act on the vehicle or not, according to whether the block ahead is occupied or clear. The present invention, however, relates to the coöperating mechanism along 25 the trackway and on the moving vehicle and is independent of the particular kind of track system employed.

The invention comprises a movable actuator along the trackway adapted to engage or clear mechanism on the moving vehicle which controls the indication, combined with mechanism along the trackway adapted to be engaged by the moving vehicle and adapted to move said actuator, there being means 35 for preventing such movement of the actuator by the vehicle under certain conditions.

The more particular embodiment of these coöperating mechanisms, hereinafter more fully described, is also included within my 40 invention.

The invention moreover includes various subsidiary features contributing to the efficiency of the mechanism and operation. Accordingly, the invention may be best summarized as comprising the combinations of 45 essential elements set out in the claims.

In the drawings, Figure 1 is a side elevation of a portion of a trackway and a truck of a vehicle both equipped with my mechanism; Fig. 2 is a vertical section of a track and vehicle mechanism showing the relative position they occupy when the vehicle is just engaging the track driver; Fig. 3 is a similar view after the vehicle is moved forward slightly showing the actuator raised

into position to engage the indicating mechanism on the locomotive; Fig. 4 is a similar view with the vehicle still farther forward and shows the position after the actuator has operated the locomotive indication; Fig. 5 is a fragmentary view, being a vertical section through a portion of the track mechanism showing the parts in the position they may occupy when the track signal mechanism has established a clear condition and the vehicle has acted on the driver; Fig. 6 is a plan of the locomotive equipment; Fig. 7 is a vertical section through the track mechanism adjacent to the main shaft; Fig. 8 is a detail, being a section across the main shaft, as indicated by the line 8—8 of Fig. 7; Figs. 9 and 10 are diagrammatic views representing respectively a bottom plan of the locomotive equipment and a top plan of the track equipment. The position of the locomotive equipment with reference to the track equipment is indicated by the broken lines *a—a* and *b—b* in these views, the correspondingly designated lines indicating the same vertical plane when the parts are in co-action; Fig. 11 is a vertical section showing track mechanism in a somewhat simplified form.

I will first describe the vehicle equipment shown. Fig. 1 illustrates a truck designated 1 which may be, for example, the truck of a locomotive tender. 2 designates the frame of the locomotive equipment of my mechanism. This frame is preferably a casting of substantially the form shown and heavy enough to withstand shocks to which it might be subjected. The truck shown is of a standard type, namely, it has a lower strap 3 and a diagonal strap 4 leading from the base of the central strut portion 5 to the bottom and top, respectively, of the journal boxes. With such form of truck, I make the casting 2 with lugs 6 on its inner side formed to occupy the triangular spaces between the straps 3 and 4 on opposite sides of the central frame 5, and I secure the casting in place by bolts 8 passing from the front of the casting through these lugs and through plates 9 which stand on the rear side of the straps. These plates preferably have inward projections, as indicated by 10, entering between the straps to insure the plate against working out of place. With such a construction, the casting may be secured very rigidly to the truck frame.

The casting 2 has a forward shoe portion or bumper 12 and a rearward shoe or bumper 13 adapted to protect the mechanism by warding off anything which may stand unduly close. Behind these shoe portions, the casting is preferably recessed or hollowed, as shown at 14 and 15, respectively, for lightness, such hollow portions providing back plates through which the bolts 8 above mentioned pass. The back of the casting, with the exception of the lugs 6, is preferably a continuous plate adapted to lie against the outer side of the truck. On the outer side of the casting, located intermediately, it has a box-like portion for containing the operating mechanism, this portion being provided by vertical walls 20 and 21 and a bottom portion 22. The casting, therefore, in the form shown, provides a bottom, ends and back for this box-like portion.

30 designates a suitable removable cover which is adapted to extend over the top and front of the intermediate box.

25 Within the box described on the vehicle equipment, is a suitable air pipe 32. In this pipe is a valve 33 adapted to close or open the pipe. 34 indicates a lever on the valve stem which is connected by a link 35 with an operating arm 36 pivoted in the box and occupying a slot 37 in the bottom plate 22 thereof. The arm 36 normally depends into position whereby it may be engaged from beneath. For this purpose it preferably has 35 a downwardly extending toe 39.

If the pipe 32 be connected with an air brake system operatable by reducing the pressure on the train line, or with a whistle or other indicator operatable by air pressure, 40 the pipe 32 will normally contain air under pressure and be normally closed by the valve 33. This will be when the parts are in the position shown in Figs. 2 and 3. When, however, the arm 36 is elevated into the position shown in Fig. 4, the lever 34 is moved to open the valve 33, thereby allowing the air in the pipe 32 to pass the valve, either escaping, reducing the pressure and applying the brake, or passing it and operating the 45 signal or other indication, as desired. 40 designates the normally idle exit pipe beyond the valve 33 which conveys the discharge through that valve and opening to the atmosphere or otherwise, as desired.

55 To hold the stem of the valve 33 in either its open or closed position against accidental displacement, I provide a detent plunger 42 mounted in a casing 43 carried on the inner face of the wall 21 and pressed 60 in opposite direction by a spring 44. This plunger occupies either of two notches 45 and 46 in a projecting portion of the lever 34, thereby holding the lever with the valve closed or open, as the case may be. The link 45 35 is slotted where it surrounds the pin in

the end of the lever 34. This enables upward movement of the arm 36 to shove upwardly the lever 34 to turn the valve stem from the closed position in Fig. 2 or 3 into the open position of Fig. 4. When the valve 70 stem is in the open position in Fig. 4, the dropping back of the lever 36 to normal position cannot return the valve, as the arm strikes its stop 48 before the upper end of the slot 49 engages the pin of the lever 34. 75

52 indicates a suitable regulating valve placed in the air pipe 32 to regulate, as desired, the effective opening of the pipe when the valve 33 operates.

The toe 39 on the lever 36 normally occupies a longitudinal recess or groove 55 formed in the under face of the base 22 of the casing, whereby that toe is protected on each side and may only be operated by something which projects up into the groove. 80 The groove is closed at its forward end by the base portion 56 of the forward shoe of the casting. At its rear end it is protected by a depending pivoted block 57 which normally closes by gravity the slot 55 beneath the plate 22. This groove, however, continues beyond the gravity block 57 through the base portion 58 of the rear shoe 13. 90

From the construction of vehicle equipment described, it will be seen that when the vehicle is moving toward the right in the illustration shown, if a suitable abutment be caused to enter the groove 55 in advance of the toe 39, such toe may engage the abutment and the valve 33 be accordingly operated with the desired result. After the toe clears the abutment, the latter may continue to occupy the groove 55, swinging upward the block 57 as it passes the abutment until 1 the casting 2 has passed forwardly beyond the abutment. It is to be noted, however, that the abutment is to be of such character that it is out of the way of the shoe 12 with its base 56 while such portion of the locomotive equipment is passing over the abutment. The most practical way to provide an abutment having these characteristics I conceive to be to have it stand normally idly beneath the path of the lower face of the shoe 12 and automatically raised after that shoe has passed the abutment and before the toe 39 has passed it. The track equipment which I have provided accomplishes this result, and will now be described.

As shown in the drawings, 60 represents the frame of the track equipment which may comprise a box-like casting having projecting wings 61 and 62 adapted to lie on top of ties 63 and be secured thereto by bolts 64. This frame may be made of such dimensions that it will stand with snugness between projecting ends of two ties which are separated by an intermediate tie in the usual position. It is accordingly only necessary to cut off

the end of one tie and shift one of the others slightly to make the two projecting tie portions abut the ends of the box 60, while the tongues 61 and 62 will extend the desired 5 distance over the top face of the tie. Extending along the top of the central box-like portion of this casting and along the top of the two ears 61 and 62, is the intermediate projecting rib 67. This rib stands parallel 10 with the track and furnishes means for protecting the mechanism hereinafter mentioned, as well as being of sufficient bulk to properly withstand shocks.

Mounted in the front plate 68 and the rear 15 plate 69 of the casting 60 is the main operating shaft 70. Rigidly mounted on this shaft within the box is an arm 71 shown in Fig. 8 as keyed to the shaft. Loosely mounted on the shaft is an arm 75. The two arms are normally connected by a dog 76 pivoted at 77 to the arm 71 and carrying a pin 78 adapted to occupy a recess 79 in the rearwardly projecting portion of the arm 75. On the outer end of the shaft 70 25 is an operating arm 80. When this arm is swung toward the right, the arm 71 swings with it and, if the parts are in their normal position, the arm 75 is also swung to elevate its left hand end. Movement of the arm 80, 30 however, toward the left simply causes the arm 71 to pull the pin 78 over the concentric portion 82 of the hub of the lever 75 without operating that lever.

Standing on the rear side of the dog 76 35 is a forked lever 85 mounted on a rock shaft 86 which extends laterally out of the track box. This fork is normally idle, but if the rock shaft is swung in the right hand direction, the left hand tine of the fork bearing against the pin 78 swings it out of the recess 79, as shown in Fig. 5, thereby interrupting the connection between the arm 71 and the arm 75. The arm 75, in the simplified form in Fig. 11, carries on its upper 45 end an abutment 90, while in the construction of the other figures, the arm 75 carries a pin 91 which occupies a slot 92 in the depending arm 93 of an abutment bar 94 which is pivoted to the casting, preferably 50 by a pin 95 extending through the projecting rib 67 and an ear 96.

The mechanism above described, it will be seen provides a driving arm 80 which may be operated to raise an abutment or 55 may operate idly, according to the position of the rock shaft 86. The abutment when idle stands along side of the protecting rib 67 and, when raised, is adapted to occupy the groove 55 of the vehicle equipment and engage the operating arm 86 therewith. To operate the arm 80, I provide a suitable lug 98 on the lower face of the bottom wall 50 of the vehicle casting. The path of this lug, as the vehicle moves, crosses the upwardly 60 projecting end of the lever 80, whereby 65

the vehicle is moving in the right hand direction, the forward face of the lug engaging the arm will swing it toward the right and will thereby elevate the abutment into the path of the toe 39 in advance of 70 that toe, provided the dog 76 has the arms 71 and 75 latched together. If these arms are unlatched, the movement of the lever 80 is idle. In any event, the movement of the lever in the opposite direction is idle. 75

To hold the lever 80 normally in its upright position, I provide a spring 100 acting on the lever and put under stress whichever way the lever moves. As shown, this spring is a compression spring, occupying 80 a barrel 101, which is pivoted on a stud 102 extending forwardly from an ear 103 at the base of the casting 60. The spring is compressed between the end surface of this barrel and a head 105 on a rod 106 which extends through the barrel head and is pivoted at 107 to a depending portion of the lever 80. 108 and 109 indicate a pair of stops for limiting the extreme movement of the lever 80. A screw-plug 104 may close 90 the barrel.

In the particular form shown, the dog 76 which forms the connection between the arms 71 and 75 is bifurcated near its upper end and lies on opposite sides of the arm 71 95 where it is pivoted to that arm. The arm 75 is bifurcated and lies on opposite sides of the arm 71, and the pin 78 extending crosswise of the dog 76 occupies notches in the two forks of the arm 75. To take the strain 100 off of the pin 77, I form the dog with an abrupt boss 110 which is adapted to occupy a notch 111 in the edge of the arm 71. The pivoting at the pin 77 is loose enough so that when the arm 71 is swung, the abrupt 105 shoulder of the boss engages the abrupt wall of the notch 111, communicating the strain through such engaging surfaces.

It is to be understood that the rock shaft 86 extends laterally to some suitable mechanism, not shown, at the side of the track, and this mechanism may swing that shaft in one direction or the other, according to track conditions. The shaft with its fork is preferably normally in the condition 11 shown in Figs. 2, 3 and 4, so that the arm 80 is normally in position to operate the abutment 90. This may be called the normal danger position. The safety position of the rock shaft and fork is indicated in 11 Fig. 5 and is accomplished by rocking the rock shaft, which action may be effected automatically, according to track conditions, or otherwise, as desired. The fork 85 preferably, in the embodiment shown, stands 12 alongside of the inner face of the back plate 69 of the box 60 and engages the rearwardly projecting portion of the pin 78, this portion showing in Fig. 7. To allow convenient access to the box while keeping it normally 13

closed, I provide suitable openings through its outer plate 68 which may be closed by suitable covers 115 and 116, Fig. 1, bolted in place.

5 It will be seen from the above description, that I have provided a track mechanism operable by the vehicle to raise an abutment into the path of indication giving mechanism on the vehicle; that such operation 10 does not result when the projecting rock shaft is turned, as it may be, for conditions of safety; furthermore, that the mechanism is non-effective should the vehicle pass rearward over it. The locomotive actuation 15 may give a signal or apply a brake automatically, as desired.

It will be noticed from an inspection of Fig. 3 that the lug 98 clears the lever 80 before the toe 39 has engaged the abutment 20 94. Accordingly, with this equipment, if the vehicle is moving slowly enough, the abutment 94 though raised, will have dropped by gravity before the toe reaches it, so that no indication will be given. If, 25 however, the vehicle is moving rapidly enough so that the abutment does not have time to drop before the toe engages it, an indication will be given. By this simple arrangement I have therefore provided a government, allowing the vehicle to pass at a slow speed over an automatic stop, while applying the brake automatically, should it attempt to pass at a higher speed. By way of illustration, the parts may be so proportioned that if the vehicle is moving five miles per hour or less, the abutment though raised will drop before the toe 39 comes over its highest point, so that no actuation of the vehicle mechanism results, but if running over five miles an hour, the toe reaches such highest point before the abutment can drop, and the vehicle actuation results. This is of particular importance where the operation on the vehicle is to automatically 40 apply the brake, for it allows a locomotive to move into an occupied block for the purpose of removing a car standing thereon, for example. It is to be understood of course that the occupancy of the block is indicated by a suitable signal and the entry of the block by an engineer when the signal is against him will be under flag and provided for by train rules.

When the air pipe has been opened by 55 the actuation of the lever 36, it is impossible for the engineer to close it from the cab, and the vehicle must come so nearly to a stop that he can dismount and manually restore the parts to normal position. I have 60 shown mechanism in Fig. 6 to provide for conveniently restoring these parts without opening the box on the locomotive equipment. The mechanism shown consists of a rock shaft 117 mounted in the walls 20 and 65 21 of the casting 2 and having a rock arm

118 which stands above the lever 34. On the outer end of this rock shaft is a knob 119 by which it may be turned. When the valve has been opened, the rock arm 118 is thereby raised, and a slight reverse twist on the knob 119 restores the parts to normal position.

Having thus described my invention, what I claim is:

1. The combination of a casing adapted to be located along the trackway, a projecting rib along the upper face of the casing, a pivoted actuator adapted to stand normally alongside of said rib, mechanism for raising said actuator, means on the vehicle for operating said mechanism, and an operating member on the vehicle adapted to engage the actuator when raised.

2. The combination of a casing adapted to stand between railroad ties and having projecting portions to rest on the upper surfaces of such ties, a rib along the upper face of the casing adapted to stand substantially parallel with the track, an actuator pivotally mounted alongside of said rib and having a portion depending into the casing, an operating member extending upwardly, and mechanism within the casing adapted to connect the operating member with the actuator.

3. The combination with a brake setting device, of a moving vehicle having an actuating member, a casing protecting said actuating member, a rock shaft, an arm rigid thereon invariably engaged by a portion of said casing, another arm loosely journaled about the rock shaft, a casing surrounding said arm in which the shaft is mounted, a lever connected with said second named arm adapted to be swung upwardly from the horizontal position to engage the actuating member on the vehicle, and means for connecting the second named arm with the first named arm according to safety or danger conditions.

4. The combination of a rock shaft, a arm rigid thereon, another arm loosely journaled about the rock shaft, a movable connection between said two arms, a driving member connected with one arm, an actuator connected with the other, and vehicle mechanisms adapted to engage the driving member and be operated by the actuator.

5. The combination of a shaft, a pair of arms, one loose on the shaft and one tight thereon, an actuator connected with the loose arm, means on a passing vehicle adapted to be operated thereby, a dog adapted to connect the tight arm with the loose arm in one direction of rocking of the shaft but not for the opposite direction, and a driving member for rocking the shaft.

6. The combination of a shaft, a pair of arms, one loose on the shaft and one tight thereon, an actuator connected with the

- loose arm, means on a passing vehicle adapted to be operated thereby a dog adapted to connect the tight arm with the loose arm, and a driving member for rocking the shaft, 5 a rock shaft, and mechanism thereon for moving said dog to idle position.
7. The combination of a casing adapted to be located along the trackway and having a protecting flange, an actuator adjacent to the protecting flange on the upper side of the casing and depending into it, a rock shaft extending from the side of the casing into its interior, an operating arm on said rock shaft on the outside of the casing, and mechanism within the casing adapted to connect said shaft with the depending portion of the actuator, comprising an arm tight on said shaft, an arm loose on the shaft, a connecting dog, and means for moving the dog into active or idle position.
8. The combination of a casing adapted to be located along the trackway, an actuator on the upper side of the casing depending into it, a rock shaft in the casing, mechanism within the casing adapted to connect said shaft with the depending portion of the actuator, comprising an arm tight on said shaft, an arm loose on the shaft, a connecting movable dog, a fork within the casing adapted to extend on opposite sides of the dog, and a rock shaft extending from outside of the casing into its interior and carrying said fork controllable by means outside the casing.
- 35 9. The combination of a casing having projecting portions adapted to rest on the upper surfaces of railroad ties, a longitudinal rib extending along the upper face of the casing, an actuating bar pivotally mounted alongside of said rib and having a portion depending into the casing, a rock shaft mounted in the casing, an arm loose on the rock shaft having a pin and slot connection with said depending portion, an arm tight on the rock shaft within the casing, a dog pivoted to the last mentioned arm and carrying a pin adapted to engage on one side a shoulder on the loose arm and be free on the opposite side, and means for moving said dog to cause its pin to clear the shoulder altogether.
10. The combination of a casing having projecting portions adapted to rest on the upper surfaces of railroad ties, a longitudinal rib extending along the upper face of the casing, an actuating bar pivotally mounted alongside of said rib and having a portion depending into the casing, a rock shaft mounted in the casing, an arm loose 60 on the rock shaft having a connection with said depending portion, an arm tight on the
- rock shaft within the casing, means for connecting the tight and loose arms, an upwardly extending arm mounted on said rock shaft, and a spring tending to hold said last mentioned arm in a definite intermediate position.
11. The combination of a shaft, a pair of arms one loose on the shaft and one tight thereon, an actuator connected with the loose arm, means on a passing vehicle adapted to be operated thereby a dog pivoted to the tight arm and adapted to engage the loose arm and having an abrupt shoulder adapted to bear against the tight arm to take the strain off of the pivot of the dog, and a frame carrying the various parts mentioned and adapted for securement to railway ties alongside of a rail.
12. The combination of a casing adapted to be secured to a moving vehicle, a movable operating member carried by the casing and depending through an opening in its base, and a bumper also carried by the casing, said casing having protecting shoes at its front and rear.
13. The combination of a casing having protecting shoes at its front and rear and an intermediate box-like portion having an opening through its bottom, an arm pivoted within the box-like portion and having a toe depending into said opening, and mechanism controlled by said arm.
14. The combination with an operating member mounted on a movable vehicle and mechanism controlled by the upward movement of said member, of an actuator mounted along the trackway and adapted to stand beneath the path of the operating member, and a pivoted arm mounted along the trackway and adapted to be engaged by the vehicle and swung forwardly, and mechanism whereby such forward movement may raise the actuator into the path of the operating member in advance of it, the vehicle freeing the arm before the operating member has engaged the actuator and the actuator tending to return to idle position, whereby the actuator may engage the operating member if the vehicle is moving at sufficient speed but will not engage it if it is moving at less than that speed, and mechanism operated at will to interrupt the connection between the pivoted arm and the actuator, whereby the movement of the arm may be idle irrespective of the speed.

In testimony whereof, I hereunto affix my signature in the presence of two witnesses.

ELMER M. JONES.
